Elisha Towne of Manchester, Vermont.

Letters Patent.

Patented Dec. 16, 1833. Registered Sept. 26, 1836.

The Schedule referred to in these Letters Patent, and
making part of the same.

To all to whom it may concern.

I, Elisha Towne of Mont Police in the County of Washington in the State of Vermont have invented a new and useful improvement in bricking stoves called Elisha Towne Improved Brick Stove, and I do hereby declare that the following is a full & exact description. This stove consists of a bottom plate cast whole excepting that part directly under the fire room and about three feet and eight inches long one half of which is somewhat elliptical and constitutes the hearth and seat for the fire room and about two feet and ten inches wide at the front of the body of the stove. The other half of the bottom plate projects off horizontally & parallel to the hearth part and is reduced to the width of twenty eight inches and is of a rectangular form. The seat of the fire room is cast in a separate piece from the other part of the bottom plate and is placed into and rests upon flanges upon the sides and ends of the main portion of the bottom plate, and is sunk two inches below the surface of the hearth directly over this part of the bottom plate, the rear and the front flange being under, and at the back side of the room, are placed. The bottom plate rests upon four legs, and the edges of the rectangular part of the bottom plate and upon the hearth are cast flanges for fixing the side plates of the stove in their proper positions. The sides are about twelve inches high and are covered by a top plate corresponding nearly in its form to the bottom plate except that part of the bottom plate which is occupied for a seat being cut off the top of the stove so that the top plate over the fire room and instead of wood between the stones in a circular hole about eight inches in diameter.

inch wider and the back part of the top plate is a hole and soldered for the outer pipe. The oven is constructed by passing plates from side to side of the outer retaining spaces of about two and one half inches between it and the bottom top and back plates. These spaces are the flues for conveying the flue and heat or smoke around the oven and to the pipe. In front of the oven and between it and the fire box, is a chamber formed on the back side by an oven plate, and in front and on the top by a thick plate. (The bottom of this chamber being formed by an extension of the bottom plate of the oven and by means of this chamber the two peripheries of the oven are equalized. Between the chamber and oven is a thick plate distinct about two inches from the chamber and reaching within about five or six inches of the top plate. The fire room occupies the front part and about one third of the body of the stove. The heat is regulated by a damper in the front part of the fire room which slides up and down in grooves directly over the fire room and two boiler places which I call doors. These doors are made by axes being placed in the rear corners of the fire room and the sides of the stove, with thin pins inserted in the bottom and top plates. They are made to form inclined and parallel when swinging in, with the sides of them staves without bottoms and with collars for resting places for kettle. These doors are cast in parts separate from the top plate when swinging forward the projecting top plates or wings cover the places of the boiler holes and prevent the passage of the fire and smoke into the room by closing the boilers off they are deprived of the greatest portion of the heat of the fire and the quantity of the heat necessary for heating is regulated thereby as a current of cold air is then permitted to pass underneath the boiler so as to draw the heat from the same. What I claim using insulation and desire to secure by letter patent is the application of the same or any like to the boiler places in heating stoves as herein described.

Witnessed for me & directed

15. Letter patent No. 1,003,613, dated December 10, 1911.

This is to certify and witness a description of improvements upon
the device described in the letter patent granted to Elika Newthuring
on the 15th day of December 1910, and making part of the same.

To all to whom it may concern:

It is known that J. Elika Newthuring of Minneapolis in the County of
Washington and State of Minnesota has invented a new and
useful improvement in Elika Newthuring's Patent, Elika
Newthuring's improvement being, and I hereby declare that the
following is a full and exact description of said improvement:
The improvement consists in a new and different form of the original
invention in these respects. The bottom plate is cast in one
piece, and one end of the cover, is a circular hole, about eleven
inches in diameter, coinciding with a similar hole in the top of a
porcelain basin often mentioned. The rear part of the bottom plate
commencing at the back side of the fire seat is one and three inches in
height and is reduced in width to twenty two inches. It extends
out from under one end of the cover, two and one half inches, so
the leg may be bolted to it. To this leg is attached to the leg is attached
and in the following manner, a pinion from the leg and about a foot
below the bottom plate, is a projection of sufficient size to admit of a
1/2 inch hole with a female screw set in the same, and of such a size
as will be required to support the weight of the porcelain and its contents
whatever may be necessary to use about it. Through this hole in
the projection is passed a made down in a vertical position
with a cavity in the upper end, which forms the hole for the lever
and pinion of motion of the porcelain. This pinion is cast solid
in a mass of porcelain which is in the form of the letter D and the
upper part of the axis is inserted into a circular hole in the bottom
plate near the leg and directly over the hole. The pinion is held
therein by a set near the bottom of which is a plate to receive the
pinion. The bottom of the cover is to be held by a bolt or pin which
is to be of a round, flat, and smooth, as the letter D of the
porcelain.

fastened to the lower edge of the sides of the furnace by bolts from the top plate. Beneath the grate is an ash pit made to slide up in flues and upon the under side of the before mentioned flues and by the sliding in and out of the ash pit it is made to regulate the draught of the air upon the fire in the furnace and to receive the ashes. The top of the furnace is a plate covering the sides thereof and projecting from the body in such form as to close the hole in the bottom in the bottom plate of the stove when the furnace is reduced or turned out for use. This top plate is pierced over the grate with a hole about eleven inches in diameter for the use of hollow and coincides with the hole before mentioned in the bottom plate directly beneath the over and through which the fire and smoke pass off after from the furnace pipe underneath the wing or projecting part of the top plate a sufficient distance and of a proper size to carry off the smoke which is let through the wing under the hole in the bottom plate when the furnace is being out. This fire is closed by swinging the furnace under and the flue and chimney passes through the corresponding holes in the top plate of the furnace and bottom plate to the fire under the same. The part sunk for the ash pit extends through the center and to the front edge of the hearth and that part of the ash pit in the hearth in front of the stove is covered by a moveable slide, as the front part of the stove is no doorway and its place is supplied by a double door. The top plate consists and differs from the top plate in the original invention in the respects that the baffle are omitted in the front part of the stove instead of the sides. The plate at each side of the stove and opposite the flues is of a semi circular form, and extends over the sides of the stove so far as to cover the wings of the flues when the doors are swinging in the front of and between the doors is no baffle placed. This plate from and in front of the baffle

is so elevated about two inches, over the oven in the elevated part and commencing at the back side of the fire seat is a
boiler hole about eighteen inches in diameter and with a baffle
plate four inches high. On the rear of the boiler hole is a hole
and collar for the stone pipe with a connecting flue between
them. The part occupied by the stone pipe extends well beyond
the body of the stove one half the diameter of the pipe hole in the
back flue is a damper, which is moved by a rod connected
with the oven and extending out of the back end of the stove
between the chamber and the fire seat, is a plate. At the end of
the chamber the sides of the stove are pierced with holes for the
ventilators of the oven. The oven is two inches and four inches
wider in this than in the original invention.

What I claim as my invention and improvement is the
construction and application of the back furnace to my original
invention in the back of stoves as herein described.

Elisha Town

Dr in portfolio

I hereby certify the foregoing additional schedule has
this twenty ninth day of September 1836 been duly annexed
to the original Patent of Elisha Town, and that the same is
duly recorded on the books of the Patent Office and that an
fifteen dollars (the duty by law required) has been paid into the U.
treasury of the United States.
